CLAIM

We claim the ornamental design for a two-piece faucet, as shown and described.

DESCRIPTION

FIG. 1 is a perspective generally isometric view of our two-piece faucet.

FIG. 2 is a top plan view of the invention.

FIG. 3 is a front elevational view of the invention.

FIG. 4 is a side elevational view of the invention, the opposite side being a mirror image of this side view.

FIG. 5 is a rear elevational view of the invention; and,

FIG. 6 is a bottom plan view of the invention.
